UNITED STATES PATENT OFFICE.

WILLIAM J. SPAULDING, OF GOLD BAR, WASHINGTON.

BOTTLE CARRIER.

Application filed August 15, 1923. Serial No. 657,514.

To all whom it may concern:

Be it known that I, WILLIAM J. SPAULDING, a citizen of the United States, residing at Gold Bar, in the county of Snohomish and 5 State of Washington, have invented certain new and useful Improvements in Bottle Carriers, of which the following is a specification.

In carrying out the present invention it is 10 my purpose to provide a carrier that is primarily but not specifically adapted for use in the carrying of milk bottles.

The primary object of my invention resides in the provision of such a carrier that 15 is extremely simple in construction and one that may be manufactured and marketed at a relatively small cost, the article embracing at the same time the desired features of efficiency and durability the nature of the same 20 being such as to be employed in conjunction with bottles of varying diameters of necks.

A still further object of this invention is to provide such a carrier that may be applied to or removed from a bottle in a simple and expeditious manner, the nature of 25 this invention being such that when once applied the same is not liable to become accidentally displaced with respect to the bottle to which it is attached.

With the above and other objects in view 30 as the nature of the invention is better understood, the same consists in the novel form, combination and arrangement of parts brought out in the following detailed description, shown in the accompanying drawing and claimed.

In the drawing wherein like reference 40 characters indicate corresponding parts throughout both of the views,

Figure 1 is a side elevational view of my improved carrier applied, and

Figure 2 is a perspective view of the carrier per se.

Now having particular reference to the 45 drawing there is shown in Figure 1 a milk bottle 5 wherein the neck portion thereof is formed at its upper end with the usual roll or beaded portion 6 for providing a shoulder. My carrier includes a bail like member made from a single length of wire and designated 7 the opposite ends of this bail member terminating in laterally extending eye portions 8.

Adapted for surrounding the neck of the 50 bottle at a point directly beneath the flange formed by said rolled or beaded portion 6 is

a pair of spring jaw members 9 which jaw members are made from a single length of wire the ends thereof being welded or soldered together. These jaw members 9 are 60 of a curvilinear form as more clearly shown in the perspective view Fig. 2 the portions of the wire forming these jaw members being bent downwardly at opposite sides as indicated at 10, the lower ends of these 65 downwardly bent portions at opposite sides of the jaws being joined together by a looped portion 11.

It is obvious that the eyelet ends 8 of said bail 7 surround the downwardly extending portions 10 at opposite sides of the jaw and serve as means for closing these jaws 9 upon the neck of the bottle when the bail is raised to the position shown in both of the figures. When it is desired to release the carrier 75 from the bottle the bail 7 is passed downwardly upon the portions 10 whereupon the jaws will manifestly spring to an open position.

The operation as well as the advantages 80 of a carrier of this type will be at once apparent to those skilled in the art and even though I have herein set forth the most practical embodiment of the invention with which I am at this present time familiar it 85 is nevertheless to be understood that minor changes may be made therein without departing from the spirit and scope of the appended claims.

Having thus described my invention what 90 I claim as new and desire to secure by Letters Patent, is:—

1. In an article of the character described, a single length of wire bent to form a pair of spring jaw members that are connected together by downwardly extending leg portions, and a bail member formed at its lower end with eyes adapted for surrounding said leg portions and to be freely slidable thereon.

2. In a carrier for milk bottles, a single 100 length of wire bent to provide a pair of jaw members joined together at their opposite ends by downwardly extending pairs of legs, loop portions connecting the legs at the bottom ends and serving as a means for 105 normally separating said jaw members, a bail formed at its opposite ends with eye portions through which extend said pair of legs and serving as a means for closing the jaws when said bail is raised.

In testimony whereof I affix my signature. 110
WILLIAM J. SPAULDING.
